SEAT OR THE LIKE

George E. Schaefer, Muskegon, Mich., assignor to Brunswick Corporation, a corporation of Delaware

Filed June 22, 1959, Ser. No. 56,486

Term of patent 14 years

(Cl. D15—8)

FIG. 1.

FIG. 2.

FIG. 3.

FIG. 1 is a plan view of a seat or the like showing my design;

FIG. 2 is a front elevation of the seat; and

FIG. 3 is a side elevation of the seat.

The dominant features of my design are shown in full lines on the drawings and consists primarily of a seat unit and a wall mountable seat supporting bracket at each side of the seat unit shaped substantially as shown and holding the seat unit in seating position so that the seat portion thereof is inclined upwardly and forwardly and the back rest portion is inclined upwardly and rearwardly, with the bottom edges of the bracket and seat portion substantially aligned.

The wall and floor surfaces shown in broken lines in FIG. 3 are for illustrative purposes only.

I claim:

The ornamental design for a seat or the like, as shown and described.
